RELATIVE HEAT FLOW DEMONSTRATOR

Frederick S. Gombert, Indianapolis, Ind., assignor to Hall-Neal Furnace Company, Indianapolis, Ind.

Application August 4, 1953, Serial No. 372,295

1 Claim. (Cl. 35—50)

This invention relates to a device for demonstrating by thermometer comparisons the relative amount of heat dissipated from a common source first primarily by radiation from that source directly from the surface of the source and secondly by applying fins to the surface of that source to compare the relative efficiency of heat flow in columns of air traveling past the heating source.

The primary object of the invention is to provide a structure wherein there is an immediate visual indication for comparative purposes to show the relative difference between use of fin radiation and non-fin radiation in a heating device such as in a warm or hot air heating furnace as is commonly used in heating dwellings and the like. The demonstrator is carried about in a portable form so that it may be available to show to prospective customers of a furnace and demonstrate the advisability of employing fin radiation.

A further important object of the invention is to employ a very simple structure utilizing an electric lamp as the heat source and a pair of thermometers in conjunction with a sheet metal housing divided into two compartments, each compartment equally receiving heat from the lamp, one compartment employing the fin radiation, and the other compartment not having the fin radiation. The cost of the construction is relatively small, yet the demonstration is exceedingly convincing.

These and many other objects and advantages of the invention will become apparent to those versed in the art in the following description of one particular form of the invention in which

Fig. 1 is a view in front elevation of a device employing the invention;

Fig. 2 is a view in top plan;

Fig. 3 is a view in top perspective of a cover for the device;

Fig. 4 is a view in vertical section on the line 4—4 in Fig. 2;

Fig. 5 is a view in top plan with the cover removed;

Fig. 6 is a view in central vertical section on the line 6—6 in Fig. 5; and

Fig. 7 is a detail in vertical section on the line 7—7 in Fig. 4.

A generally rectangular housing 10 is formed to be open across its top side, and to have several air intake openings at the lower end thereof, these openings herein being shown as triangular cut outs 11 in the front, rear, and side walls of the housing.

The housing 10 has a strap 12 fixed centrally across the interior thereof, and this strap 12 has a sufficient width to receive a compression socket base 13 therethrough and thereagainst. This socket 13 is of standard construction, comprising a body 14 with a base cap 15 which screw threads upon body 14, which latter extends through the strap 12, all in a usual and well-known manner, this type of socket being normally termed a sign type of socket.

The strap 12 is spaced well down into the housing 10,

2

and at least a sufficient distance to receive a lamp 16 therein with the upper end of the lamp being below the top edge of the housing 10. This lamp 16 is of a type generally known as a refrigerator type lamp, and has a filament 17 supported to be within a horizontal plane approximately, and is approximately circular in shape, or at least extends circumferentially around inside of the lamp a distance approaching a circle.

A pair of plates 18 and 19 are fixed to the side walls 10 of the housing 10 and interiorly thereof, to be in a median plane and to have opposing edges 20 and 21 relatively closely conforming to the contour of the lamp 16 so that the lamp 16 may be entered down between those plates 18 and 19 to have substantially half of the lamp on one side of the plane of those plates, and the other half on the opposite side. The upper edges of these plates 18 and 19 terminate a distance slightly above the diameter of the bulbous portion of the lamp 16. The socket is rotatably adjusted around on the strap 12 to bring the lamp 16 into that position whereby the filament 17 will have an equal portion on each side of the plane of the plates 18 and 19.

The upper end portions of the plates 18 and 19 each carry a lip 22, Fig. 7, spaced from the face of the plate 25 so as to receive the lower end of a slide gate 23 which is entered from the top of the housing and is cut out from its under side to have an edge coming down into substantial contact with the upper end portion of the lamp 16. The gate 23 along with the plates 18 and 19 forms an effective partition vertically and centrally through the housing 10. The upper edge 24 of the gate 23 terminates at the upper edges of the housing 10.

On one side at least of this central partition, there is a spring-like tongue 26 secured to the wall of the housing 35 and normally projecting inwardly and downwardly from that wall, herein shown as a wall 27, Fig. 6.

A fin radiator is built up following the construction as shown in Patent No. 2,644,225 and has those dimensions which will permit the radiator generally designated by the numeral 28 to be inserted down into the housing 10 on one side of the gate 23. The radiator 28 is pushed downwardly until its lower end rests on the strap 12, Figs. 5 and 6, and the inner ends of the fins 29 rest in intimate contact with the lamp 16, at the major diameter 45 portion of the lamp.

As indicated this radiator 28 is made up out of an enclosing outer wall 30 from which extend the fins 29, and between the adjacent fins 29 there is a vertical flue or channel provided. The tongue 26 compresses against the wall 30 to carry the radiator into the position of fin contact with the lamp 16, so that heat generated by the lamp 16 can be conducted in part from the radiator side to those fins 29. As is to be noted in Fig. 6, the actual contact between the fins and the lamp 16 is very slight due to the curvature of the lamp.

A cover as indicated in Fig. 3 is made to fit over the upper end of the housing 10, this cover having a major enclosing plate 32 with a downturned flange 33 extending therearound so that the flange may frictionally fit over the upper marginal end portions of the side walls 60 of the housing 10, Fig. 4, and be retained thereover. The plate 32 has a pair of rectangular flues 34 and 35 extending upwardly therefrom, and opening through the plate 32. These flues 34 and 35 are spaced apart one 65 from the other so that they will have their under openings one on each side of the gate 23. At the lower end of each flue 34 and 35, there is a tongue 36 and 37 respectively extending horizontally out from the under side of the plate 32 a short distance. In each of these 70 flues 34 and 35 there is placed a thermometer 38 and 39 respectively to have the lower end of the thermometer in each instance rest on the tongues 36 and 37 and rest

in an inclined manner as indicated particularly in Fig. 4 across the upper outer edge 38 of the flue 36 and edge 39 of the flue 35. These thermometers will block off a considerable cross sectional area of each of the flues, yet there will be sufficient clearance to permit a flow of air through the flues around the thermometers, and particularly through openings 40 in each of the thermometers adjacent the bulbs 41.

When the lamp 16 is energized, heat from the filament 17 will cause upcurrents of air on each side of the plates 18, 19, and the gate 23, to flow through the housing 10 and out through the respective flues 34 and 35. After the heat flows have been established, in a short interval of time, the thermometers 38 and 39 will begin to register a difference in temperature, the thermometer 39 on the fin side of the lamp 16 beginning to show higher indications of temperature than does the other thermometer 38. The thermometers will finally come to indicate as much as from 20 to 22 degrees F. difference between the two air flows, that is the higher temperature will be registered on the fin side of the lamp 16. This will happen in spite of the fact that many of the passages upwardly through the radiator 28 between the fins 29 will be block off on the under sides by reason of those fins resting on the strap 12. Normally in a furnace, the fins 29 will be in contact with the fire dome or combustion chamber throughout the lengths of fins.

To replace the lamp 16, all that has to be done is to remove the cover, lift the gate 23, and then unscrew the lamp 16 from its socket 13 and put in a new one as desired. The gate 23 may then again be lowered and the cover replaced over the housing 10 and the demonstrator is ready for use again with the thermometers 38 and 39 put into position in their respective flues 34 and 35. Incidentally, these thermometers 38 and 39 are simply loosely placed within the flues so that they may be removed for convenience in carrying the demonstrator about.

Thus it is to be seen that I have devised an exceedingly simple yet most effective means for demonstrating the differences in heat transmitted through air flow columns from a heat source having one portion thereof fin radiated and the other side non-fin radiated. While I have herein shown and described the device in the one

particular form, it is obvious that structural changes may be employed without departing from the spirit of the invention, and I therefore do not desire to be limited to that precise form beyond the limitations which may be imposed by the following claim.

I claim:

A heat flow comparator comprising a housing open at its top and having lateral openings in the lower end portions of its sides; a heating member centrally mounted within the housing above said lateral openings and spaced from the sides of the housing; a centrally, vertically disposed partition across said housing cut out to extend in close proximity to and in substantially a common plane across and down the sides of said heating member; said partition being in two parts, one part being fixed stationary around a lower portion of the heating member, and the other part being removably positioned across the upper portion of that member; a fin radiator compressibly held with fin ends against said heating member on one side of said partition and defining vertical air flows along said member; a cover engaging the upper end of the housing and bearing across said partition other part, retaining that other part in position; a pair of stub flues, each of rectangular and equal cross-section carried by and extending vertically from said cover, one flue opening through the cover on each side of said partition; each flue opening having a thermometer supporting ledge entering therein from common sides; and a thermometer having a back of a width approaching the width of said flues and resting by a lower end on said ledge and inclined therefrom to rest on the opposite upper side of said flue in each instance; said thermometer back in each instance carrying a bulb exposed through an opening in the back within the flue, and from which bulb a thermometer column extends up along the top side of the back.
